PARTITION CONSTRUCTION

Wesley W. Eager, Pasadena, Calif.

Application October 14, 1941, Serial No. 414,912

3 Claims. (Cl. 20—4)

This invention relates to building construction, and more particularly to partitions of the type commonly employed to divide a relatively large room into a plurality of smaller enclosures, thus making possible the provision of a plurality of private or semi-private offices or rooms at a materially smaller cost than required for solid wall construction.

An object of my invention is the provision of a novel partition construction of the general character indicated, in the form of the necessary number of separate units, each of which is produced as a unitary structure complete in itself, constructed to exact, final size, as determined by the requirements of the ultimate installation, thereby making for maximum efficiency of manufacture and exactitude of dimensions, as well as assuring nicety of fit between adjacent portions of the ultimate partition, inasmuch as the construction of the several units can be completed under factory or shop conditions, with the most efficient machinery and other equipment, leaving only the final assembly of the several units to be performed at the location where the partition is to be erected.

A further object in this connection is the provision of a partition construction as described, wherein certain ones of the constituent units are provided with means adapted to interfit with others and thereby aid in the assembly of the finished partition to such an extent as to reduce materially the labor and cost of its erection.

Another object of my present invention is to provide a partition construction in the design of which particular attention has been directed to facility of installation with perfect accuracy; i. e., straight, level, and plumb, without any dependency upon whether or not the floor upon which the partition is to be installed is level or flat.

A more detailed object in this connection is the provision of a partition construction embodying a horizontal stretcher member of sufficient rigidity to enable it to function as an inverted beam and mounted at predetermined elevation above the floor by suitable supports adjacent the ends of the stretcher. The beam and the supports differ in function from more conventional construction in that they are designed and interconnected toward the end of resisting motion in an upward direction, for the reason that the panels of the partition are retained in position by being forced upwards into retentive abutment with the underside of the stretcher.

Yet another object is to provide a jack particularly adapted for use as a portion of the partition

construction of the present invention in that it is of such small dimensions that it is adapted to be interposed between the bottom edge of one of the panels without necessitating providing an opening for its accommodation larger than that customarily employed for air circulation in order to meet the requirements of modern air conditioning, and yet capable of developing a pushing force ample to press the panel against the stretcher sufficiently firmly to insure rigidity of the assembled structure.

A more general object of my invention is to provide a partition construction adapted to be erected in the location of its final installation with the greatest of ease, within a minimum of time, and with the least disturbance to persons in the immediate vicinity, and yet, when installation is completed, presents an appearance of permanence, and is possessed of strength and rigidity, considerably in excess of partitions constructed more conventionally.

A still further object is to provide a partition construction as described wherein means are provided at frequent intervals throughout the length of the partition for the accommodation and concealment of said service facilities as telephone and buzzer wires, electric service, and even tubes for water, gas and air service.

The invention possesses other objects and valuable features, some of which, with those enumerated, will be set forth in the following description of the preferred embodiment of my invention illustrated in the drawings accompanying and forming part of the specification. It is to be understood that I do not limit myself to the showing made by said drawings and description, as I may adopt variations of the preferred form within the scope of my invention as defined in the claims.

Referring to the drawings:

Figure 1 is a view in front elevation of a length of partition constructed and erected in accordance with the principles of the present invention.

Fig. 2 is an enlarged detail view in horizontal section taken upon the line 2—2 of Fig. 1 with the direction of view as indicated. Portions of the figure are broken away to reduce its size.

Fig. 3 is an enlarged perspective view of the upper portion of one of the post members of my improved partition construction which serves as a corner of the partition.

Fig. 4 is an enlarged, horizontal, compound, sectional view, the planes of sections being indicated by the lines 4—4 of Fig. 1 and the direction of view by the arrow.

Fig. 5 is an enlarged, horizontal, sectional view taken upon the lines 5—5 of Fig. 1 with the direction of view as indicated.

Fig. 6 is a horizontal, sectional view drawn to reduced scale, the plane of section being indicated by the line 6—6 of Fig. 1 and the direction of view by the arrow.

Fig. 7 is an enlarged, transverse, vertical sectional view, the plane of section being indicated by the line 7—7 of Fig. 1 and the direction of view by the arrow.

Fig. 8 is a more highly enlarged, detail view taken in vertical, medial section through one of the jacks used in conjunction with the panels of my improved partition construction and is showing the manner of cooperation of the jack with said panel.

Fig. 9 is a view similar to Fig. 8, but showing the jack employed to support a pair of panels instead of a single panel as in the case of Fig. 8.

Fig. 10 is a bottom plan view of the jack. This figure may be considered as a horizontal, sectional view taken upon the line 10—10 of Fig. 9 with the direction of view as indicated.

Specifically describing my improved partition construction in what at present appears to be its preferred embodiment, Fig. 1 illustrates the partition as comprising four basic portions, each of which is adapted to be constructed separately as a unit complete unto itself but arranged to cooperate with the other units in such a manner as to facilitate assembly thereof into a complete partition structure which possesses an appearance of greater permanence and which is possessed of greater strength and rigidity than are partitions constructed according to more conventional plans. These four units comprise the panels 11, the horizontal header or stretcher 12 extending across the tops of the panels 11, the post or pillar members 13 which operate to maintain the stretcher 12 at predetermined elevation above the floor 14 and the jack 16 which cooperates with the panels 11 and whose function it is to press the panels upwards into retentive abutment with the under surface of the stretcher 12.

As is clearly shown in Fig. 1 the panel may take any one of several forms, to-wit: the panel 11 may be constructed entirely of wood or other non-transparent material as is illustrated at 11-A, or it may be provided with a window light 11-B, or it may be constructed with a wicket 11-C. Similarly, the panel 11 may be provided with hinges 17 and suitable latch hardware 18, thus providing a door 11-D, in which case the adjacent panels 11 or post members 13, as the case might be, are provided with suitable jambs 19, as illustrated in Figure 2. In any event, however, the panel as in the case of each of the other four units of the partition is adapted for factory or shop manufacture, i. e., it is not my intention that the materials of which the panels are to be constructed be cut, interconnected and assembled at the point of ultimate installation where such operations would necessarily have to be performed largely by hand. On the contrary, the constituent elements of each panel 11, such as the rails 21, stiles 22 and sections 23 of paneling can be cut, interfitted and glued up in the shop or factory where the proper machinery for the most expeditious and economical manufacture of such products can be employed. In fact, so efficient is the manner of interconnection between the four units comprising the completed partition of my invention that I have found that under certain circumstances it is advantageous even

to apply the final finish to the unit at the shop, since no cutting, fitting, nailing or similar hand work is required to mount the panels in their supporting framework as will appear more clearly hereinbelow.

The framework for each group of panels 11 is comprised of the associated stretcher 12 and two spaced vertical posts 13; and as hereinabove pointed out these members also are subject to manufacture in the shop where conditions for their production expeditiously and accurately are most expedient. The stretcher member 12 can be of any suitable design either of solid construction or, as shown in Fig. 7, it may be of box-like construction consisting of opposed sides 31 interconnected by top and bottom 32 and 33, respectively. All four of these members extend longitudinally and are of sufficient length to define the stretcher 12 in the length desired for the particular installation. One reason that construction of the stretcher 12 in box-like form as described is that it presents a hollow interior 34, thus leaving an opening for the sliding reception of a key 36 at each end of the stretcher 12. Preferably suitable ornamentation is applied to the outer surfaces of the side members 31, such as a longitudinally extending groove 37 which imparts to the stretcher 12 the appearance of a conventional partition header. A longitudinally extending groove 38 is provided in the under surface of the header 13, a convenient method of providing this groove being by means of a pair of spaced strips 39 of molding secured to the lower edges of the side members 31 and/or to the under surface of the bottom member 33 as clearly shown in Fig. 7. This groove 38 is adapted to receive the upper edges of the panels 11 associated with that stretcher and retain them against lateral displacement.

The stretcher 12 is carried by two of the pillars or posts 13 disposed vertically and in suitably spaced relation to receive the stretcher 12 between their upper ends. Here again the member is adapted to be constructed in accordance with the requirements of the particular installation for which the member is being designed. For example, the post 13a at the left hand end of Fig. 1 is constructed to function as a corner member, i. e., where two perpendicularly arranged runs of the partition meet, whereas the post 13b at the right hand end of Fig. 1 functions as a juncture between a lateral run 41 (see Fig. 6) of the partition and the body or main portion of the partition at some point intermediate the end of the latter. The post 13a is in the form of two vertically disposed flanges 42 and 43 arranged at right angles with respect to each other; whereas the post 13b consists of three flanges 44, 45, and 46, two of which are in planar alignment with each other and the third is positioned in such a manner as to constitute the perpendicular bisector of their plane. It is readily apparent, therefore, the posts 13 lend themselves toward production in numerous other forms, for example, with four flanges meeting at right angles so as to serve as the point of juncture of two partitions that cross each other or in certain installations the flanges might be disposed at angles other than right angles. In all cases, however, each post 13 is a separate, unitary and self-contained unit complete in itself. Its flanges 42 and 43, or 44, 45 and 46, as the case might be, are interconnected as by gluing in compliance with conventional practice before they are taken to the location where the partition is to be installed.

Each of the posts 13 is also provided at its upper

end with a header 47 (see Fig. 3) preferably corresponding in shape, size and ornamentation to the stretcher 12 with which they are to cooperate. Further, the posts are so proportioned and arranged that their headers 47 are supported at the same elevation above the floor 14 as, and in alignment with, the header 12 which they are to support. Consequently, in the completed assembly the headers 47 at the upper ends of the posts 13 present the appearance of being direct continuations of the stretchers 12 with which they are associated.

It is readily apparent, therefore, that, since each post 13 with its associated header 47 is a complete unitary structure manufactured and glued up in the factory, the most difficult operations in the production of the partition can be performed in the shop or factory with the aid of the best machinery intended for that particular purpose. Consequently all such difficult steps as cutting miters, glueing up in exact relative position of two different parts of a unit and the like, can be performed where manufacturing conditions are best suited for that particular purpose.

Whereas, as far as appearance is concerned, each of the posts 13 is similar to corresponding members of conventional partitions, in function they are quite different inasmuch as they are intended to be subjected to tension instead of compression. That is to say, each of the posts 13 operates to retain the stretcher 12 which they support against movement in an upward direction. This derives from the fact that the panels 11 associated with each stretcher 12 abut against the undersurface of the stretcher and are forced upwards thereagainst with sufficient strength to assure their retention in selected position. Accordingly, each stretcher 12 operates as an inverted beam and the posts 13 which are connected to its ends are subjected to tension inasmuch as they operate to prevent the beam which they carry from moving upwards. Accordingly, means are provided for securing the lower ends of the posts 13 to the floor 14 retaining them not only against lateral displacement but also against upward movement away from the floor. For purposes of economy and uniformity of appearance I prefer to employ one or more of the same jacks 16 as those employed to press the panels upward, for the purpose of anchoring the lower ends of the posts in position, but in this instance instead of operating as jacks they will function merely as hold-down brackets. Jacks 16 functioning in this manner are illustrated in Fig. 1 as indicated at 51. As clearly shown in Figs. 8, 9, and 10 each of these jacks comprises a relatively low base or housing 52 having a vertical bore 53 interiorly threaded as indicated at 54 to receive the threaded end of a spindle 56 which is only slightly longer than the bore 53. The purpose behind the use of these members constructed of minimum length is to reduce the overall height of the jack 16 to the smallest possible figure consistent with the capability of the instrument to develop the necessary strength in pushing the panels 11 upwards. Means are provided for preventing lateral displacement of the jack 16 even when it is not fastened down to the floor 14 such as by means of a plurality of relatively sharp ridges or teeth 57 formed upon the bottom or under surface of the body 52. The bottom is also formed with a screw hole 58 preferably at the center thereof through which a screw 59, or the like, may extend to hold the jack 16 securely down upon the floor 14 as indicated in Fig. 9. A sup-

porting bracket 61 rests upon the upper end of the spindle 56 and preferably is secured thereto by a swivel connection such as opposed offset flanges 62 seated within a groove 63 in the periphery of the spindle 56 adjacent its upper end, the engagement between the flanges 62 and the spindle 56, however, being sufficiently loose to permit the spindle 56 to turn while the bracket 61 remains stationary. Two forms of bracket 61 are illustrated, that in Fig. 8 being provided with an upwardly extending flange 64 at one end of the bracket, and the jack 16 in Fig. 9 being provided with a bracket 61a having two opposed, upwardly extending flanges 66 and 67. The former, i. e., the jack 16 illustrated in Fig. 8, is intended to be employed where it supports only one panel 11 or an anchoring post 13 only. Hence, this jack 16 is disposed entirely under only one of these members. In Fig. 9, however, the jack 16 is disposed under two adjacent panels 11 and functions to support both of them. Accordingly, the centerline of the jack 16 is disposed directly under a line midway between the two proximal edges of these associated panels. Furthermore, the flanges 66 and 67 of the bracket 61a, being spaced apart a predetermined distance as clearly shown in Fig. 9, function as spacers to determine accurately the precise spacing between the panels 11 associated with that jack. Preferably the upper end of the spindle 56 is also provided with an enlarged annular portion 68 within which a plurality of holes 69, preferably four, are formed at equal distances throughout the periphery of the spindle, these holes being adapted to receive a pin whereby the spindle can be rotated within its body 52 for the purpose of raising or lowering the spindle 56 and thereby causing the device to function as a jack.

It is readily apparent, therefore, that a wide range of adaptability of the jacks 16 is afforded. In their preferable manner of application, however, one jack 16 is located below each space between adjacent panels 11 and below each space between a panel 11 and a post 13, except where one of such panels is hingedly mounted to enable it to serve as a door, and in those cases a jack 16 is placed entirely under the fixed element of that pair, thus avoiding interference with movement of the door and obstruction of the doorway. This arrangement preserves uniformity of appearance throughout the length of the partition and it also is possessed of the advantage that it places at least two jacks in association with each post, thereby adding to the security with which each post is held down in opposition to the upward thrust of the jacks 16 associated with the several panels on both sides of that post. As stated, it is desirable, in order to preserve uniformity of appearance, that each jack be so placed that it straddles the space between two panels or the space between a panel and a post, but in the latter case the jack is secured to the post only, its sole function being to hold that post down. At such locations in the installation, reliance is placed in the jack associated with the opposite edge of the associated panel for the support of that entire panel. Although this arrangement provides support for that panel adjacent one side edge only, in most instances it is not conducive to a "cocked" position of the panel due to the fact that the upper edge of the panel, which is quite accurately perpendicular to the side edges, is pressed firmly against the horizontal stretcher member 12. However, if and when any tendency for any such cocked position of a panel

might develop, a second jack can easily be placed under the sagging corner of the panel to support the panel accurately in its proper position.

As stated, in the assembled partition the headers 47 on the upper ends of the several posts 13 appear as continuations of the stretchers 12 with which they are associated. Accordingly, it is desirable to employ invisible means for interconnecting the stretchers 12 with their associated posts 13. Toward this end the keys 36 which are employed for this purpose are concealed entirely within keyways which are provided by the hollow interior 34 of each of the stretcher members 12. Each of these keys may conveniently take the form of a piece of wood of suitable length and of cross section which permits it to be slidably received within the hollow interior 34 of the stretcher 12. Such a key is illustrated in Fig. 3. Just before placing the stretcher 12 in operative relation to its supporting posts 13, one of these keys is slid into each open end of the stretcher. The posts 13 which are to serve as supports for the stretcher having first been placed accurately in position and fastened securely down to the floor 14 by one of the screws 59 extending to the bottom of each of the jacks 16 associated with each post and by a screw 74 extending through the flange 64 of each of those jacks, the stretcher 12 is then placed into position between and interconnecting the headers 47 and the upper ends of the posts 13. The key 36 at each end of the stretcher is then worked across the line of juncture between that end of the stretcher and the associated post 13, for which purpose a small opening 76 (see Fig. 7) is provided in the upper member 32 of the stretcher 12 adjacent each end thereof. After the key has been worked to approximately the position wherein one is illustrated in Fig. 3 it preferably is securely fastened in that position as by one or more wood screws 77 driven through the upper member 32 of the stretcher or the corresponding member of the header of the post or both.

After the stretcher 12 has thus been positioned at predetermined elevation above the floor 14 and securely anchored in that position against being pushed upward, the several panels 11 which are to be associated with that stretcher are then placed in position by engaging their upper edges within the groove 38 in the under surface of the stretcher. In so placing the panels care should be exercised that they be spaced apart far enough to leave a slot or opening 78 therebetween, corresponding to the spacing between the outer facing of the flanges 66 and 67 of one of the jacks 16. This not only permits insertion of the jack 16 in such a manner that each jack supports two panels but it also assures that the space 78 between panels is accurately of the necessary width to receive the two opposed legs 79 (see Figs. 4, 5 and 9) of the spring bracket 81 which are secured to the inner surfaces of the batten 82 adapted to be received in covering relation with the openings 78 between panels 11 on either or both faces thereof. Preferably the configuration of the outer faces of the battens 82 correspond to those of the jambs 19 so as to present a completed structure, all the visible details of which are in harmony.

One of the important features of this detail of my invention is that such a space 78 is left in the partition at frequent intervals throughout the entire length thereof and as these spaces 78 extend all the way from the top to the bottom

thereof they serve conveniently as wire chases for the reception of wires for telephone or electric light service or, in fact, for tubing for compressed air and for gas service thereby making such services conveniently extendable at any point throughout the entire length of the partition but keeping them completely concealed.

It is apparent from the hereinabove description that the jack 16 associated with the simple panel 11 should be operated to press those panels upward against the underside of the stretcher 12 associated therewith. In fact, this pressure should be of sufficient magnitude to take the entire weight of the stretcher members 12 and to impose at least a certain amount of tension upon the posts 13 associated therewith thereby enhancing the security of the interengagement between the panels 11 and the stretcher 12. In this manner a resultant structure is obtained which is possessed of a surprising amount of rigidity. In fact, a partition constructed in accordance with the principles of the present invention is found to be more rigid than most partitions constructed according to more conventional design.

Another important feature of the construction of the present invention is that all the posts 13 and panels 11 are so elevated above the supporting floor by the jacks 16 that a space 83 is left below their lower ends. This space has proven itself of real value inasmuch as it permits freedom of circulation of air between the several compartments separated by the partition. The importance of this feature is most apparent when used in an air-conditioned building which heretofore required the employment of a grill in the door of the partition separating each two adjacent compartments so as to permit maintenance of the same atmospheric conditions in both. The space 83, however, is even more desirable than the more commonly employed grill intercommunication for the reason that not only does it provide for far more adequate flow of air between adjacent apartments but it also eliminates drafts. However, if it should be desired in any particular type of installation to close the space 83 beneath the partitions, it is entirely feasible to employ a baseboard construction such as that indicated in dotted lines 84 in Figure 7. Since the base 51 of each of the jacks 16 is slightly wider than the lower ends of the panels 11 it is preferred that if such a baseboard construction be employed, the lower edge of the inner face of the baseboard be relieved as indicated at 85 to accommodate the base 51 of the several associated jacks 16.

In certain installations it may be desirable to employ a partition of lesser height than that illustrated such for example as a counter wherein a horizontal shelf is at the upper edge of a partition of approximately three feet height. The only difference between such an installation and that hereinabove described is that the posts and panels of this shorter partition would be shorter than those of the modification already described. Furthermore, in certain installations it may be desirable to close the space between the stretcher 12 and the ceiling 86. This can easily be accomplished through the expedient of transom paneling of any suitable design, indicated at 87 in Figs. 1 and 7, though it should be understood that such overhead paneling is not necessary for the rigidity and strength of my improved partition.

I claim:

1. In a knockdown partition construction, a pair of spaced posts, releasable means for fastening the lower ends thereof to the floor, a horizontal stretcher secured to said posts adjacent the upper ends thereof, the under side of said stretcher having a groove extending longitudinally thereof, a panel disposed below said stretcher with its upper end seated within said groove, and a jack interposed between the lower edge of said panel and the floor and operable to raise said panel into retentive abutment with said stretcher, said panel pressing against and at least partially supporting said stretcher.

2. In a knockdown partition construction, a pair of spaced posts, releasable means for fastening the lower ends thereof to the floor, a horizontal stretcher secured to said posts adjacent the upper ends thereof, the under side of said stretcher having a groove extending longitudinally thereof, a panel disposed below said stretcher with its upper end seated within said groove and pressing upwards against said stretcher and supporting at least a portion of

the weight thereof, a jack interposed between the lower edge of said panel and the floor and operable to raise said panel into retentive abutment with said stretcher, and guide means on said jack restraining the lower end of said panel against lateral displacement.

3. In a knockdown partition construction, a pair of spaced posts, releasable means for fastening the lower ends thereof to the floor, a stretcher interconnecting said posts, means for fastening said stretcher to said posts at predetermined elevation above the floor, said fastening means comprising a key associated with each end of said stretcher and slidably within aligned parts of a keyway in said stretcher and the associated post optionally to extend across the juncture therebetween to fasten said stretcher to said post or to be withdrawn therefrom to release said stretcher from said post, a plurality of panels disposed in planar alignment below said stretcher and means for pressing said panels upwards into retentive abutment with the under surface of said stretcher.

WESLEY W. EAGER.
